United States Patent Office.

THOMAS L. LUDERS, OF OLNEY, ILLINOIS.

Letters Patent No. 92,328, dated July 6, 1869.

IMPROVEMENT IN DEVICES FOR HOLDING THREAD WHILE DOFFING IN SPINNING-MACHINES.

The Schedule referred to in these Letters Patent and making part of the same.

To all whom it may concern:

Be it known that I, THOMAS L. LUDERS, of Olney, in the county of Richland, and State of Illinois, have invented certain new and useful Improvements in Bobbin and Thread-Holders; and I do hereby declare the following to be a full, clear, and exact description thereof, sufficient to enable those skilled in the art to which my invention appertains, to fully understand and use the same, reference being had to the accompanying drawings, forming part of this specification, and in which the figure represents an elevation and partial section of my improved bobbin and thread-holder.

This invention relates to an improvement in the bobbin and thread-holder for which Letters Patent were granted to me, dated October 20, 1868.

I have found from practical experience that the bobbin and thread-holder, above referred to, is very economical in its use, as regards yarn saved, over the bobbin and thread-holder in ordinary use; but it is liable to objection, on account of the time lost in fastening the end of the yarn between the spring and the base of the bobbin.

To obviate this defect is the object of my improvement; and

It consists in the employment of a spring under the base of the bobbin-holder, to hold the yarn firmly, by pressing against the bobbin-holder and raising it to meet two or more hooks, with the end of the yarn between them.

In the accompanying drawing—

G represents the rail, and

b is the bobbin on the spindle, having its lower end resting in the case or bobbin-holder c.

e is a spiral or other spring, having its lower end resting on the base, m, which encircles the spindle, but is capable of being slid upward thereon, the upper end of said spring pressing against the base of the bobbin-holder c, and keeping it forced upward, to meet

two or more hooks, d d, leaving the end of the yarn clasped between the hooks and the bobbin-holder or case c.

Attached to the sliding base, m, are four or more wires, g, whose upper ends bear against the base of the bobbin b, and encircling the spindle, and concentric with the spring e, is another spiral spring, f, whose tendency is to force the base, m, and the wires g, downward, so that the bobbin may occupy its proper place on the spindle.

The support n serves to prevent the base m being forced too far downward by the springs.

When it is desired to doff or change the full bobbin for an empty one, the base, m, is forced upward, and the wires g, attached thereto, serve to loose the bobbin from the spindle, the spring e, at the same time, being compressed, so that the yarn, which has been wound below one or more of the hooks d, may be held tightly between said hooks and the case c.

The advantages attained by the employment of the hooks outside the case c, and by clasping the end of the yarn between them, are as follows: economy of time in making the change from full to empty bobbin, and no loss of yarn.

Having thus fully described my invention,

What I claim as new, and desire to secure by Letters Patent, is—

1. The hooks d d, in combination with the case c, spring e, base m, and support n, substantially as described.

2. The combination of the wires or rods g g, spring f, base m, and support n, substantially as described.

To the above I have signed my name, this 24th day of March, 1869.

THOS. L. LUDERS.
